(57) **CLAIM**

The ornamental design for a display screen portion with icon, as shown and described.

DESCRIPTION

The file of this patent contains at least one drawing/photograph executed in color. Copies of this patent with color drawing(s)/photograph(s) will be provided by the Office upon request and payment of the necessary fee.

The present application is related to U.S. Design patent application Ser. No. 29/623,813, U.S. Design patent application Ser. No. 29/623,844, U.S. Design patent application Ser. No. 29/623,815, U.S. Design patent application Ser. No. 29/623,826, and U.S. Design patent application Ser. No. 29/623,833, filed concurrently herewith, the entire disclosures of which are incorporated herein by reference.

FIG. 1 is a front view of a first embodiment of a display screen portion with icon, showing the new design;

FIG. 2 is a second embodiment thereof; and,

FIG. 3 is a third embodiment thereof.

The dash-dot broken lines showing the display screen portion depict the bounds of the claimed design and form no part thereof.
